(57) **CLAIM**

The ornamental design for a vehicle door hinge cover as shown and described.

DESCRIPTION

FIG. 1 is a top right perspective view of a left vehicle door hinge cover illustrating an embodiment of our new design; FIG. 2 is a top left perspective view thereof;

FIG. 3 is a front side view thereof;

FIG. 4 is a back side view thereof;

FIG. 5 is a left side view thereof;

FIG. 6 is a right side view thereof;

FIG. 7 is a top view thereof; and,

FIG. 8 is a bottom view thereof.

The broken lines in the drawings are included for the purpose of illustrating environmental structure and form no part of the claimed design.

1 Claim, 5 Drawing Sheets
